UNITED STATES PATENT OFFICE.

GEORGE PERCY JACKSON, OF NEW YORK, N. Y., ASSIGNOR TO COMBUSTION ENGINEERING CORPORATION, OF NEW YORK, N. Y., A CORPORATION OF NEW YORK.

FURNACE.

Application filed March 29, 1922. Serial No. 547,678.

The present invention has special reference to means for assisting combustion in a furnace, and reducing liability of clinkers and other injurious deposits forming on the 5 wall of the fire-box of a furnace.

An object of the invention is to provide a novel and improved means of this character which is particularly adapted for use in a pulverized fuel furnace.

10 Another object of the invention is to provide a combustion chamber for a pulverized fuel furnace having its bottom wall of novel and improved construction.

15 The several features of the invention whereby the above mentioned and other objects may be attained will be clearly understood from the following description and accompanying drawings, in which—

20 Fig. 1 is a longitudinal vertical sectional view, partly in elevation, of a pulverized fuel furnace embodying the features of the invention in their preferred form;

Fig. 2 is sectional plan view taken on the line 2—2 of Fig. 1;

25 Fig. 3 is a vertical sectional view taken on the line 3—3 of Fig. 1;

Fig. 4 is a sectional elevation, on an enlarged scale, taken on the line 4—4 of Fig. 2;

30 Fig. 5 is a detail inverted view in perspective of a component part of the bed or bottom of the fire-box;

Fig. 6 is a transverse sectional view, on an enlarged scale, taken on the line 6—6 of Fig. 2; and

35 Fig. 7 is a detail inverted view in perspective of a component part of the bed or bottom of the fire-box.

The pulverized fuel furnace illustrated in the drawings is provided with a steam boiler 2, and a fire-box 4 having longitudinal side walls 6, front wall 7, rear or bridge wall 8 and a top wall 10. A pulverized fuel nozzle 12, suitably connected with a source of fuel supply, is mounted in the top wall and 40 is so arranged as to direct pulverized fuel downwardly into the fire-box. In this type of furnace the combustion of the fuel takes place while the fuel is in suspension and the furnace draft tends to direct the suspended 45 mass of burning fuel and the gases upwardly to the boiler as indicated in Fig. 1 of the drawings.

50 As illustrated the fire-box is provided with two piers 14 which are arranged on the bottom wall 15 of the fire-box and adjacent the

side walls 6, respectively. The fire-box is further provided on its bottom wall with a series of three piers 17, the outer piers of the series being spaced from the piers 14 and from the intermediate pier of the series, said 60 spaces between the piers forming troughs. The front wall of the fire-box is provided with openings 18 at the forward ends of the troughs which are closed by doors 19.

Each of the piers 17 consists of side walls 20 and an intermediate partition 22 which is spaced from the side walls, these parts of the piers being made of fire-brick. The top of each pier 17 consists of blocks 24 of refractory material that are arranged in end to end 65 relation and rest upon and are cemented to the top of the side walls 20 and the intermediate partition 22 with the longitudinal sides of the blocks projecting beyond the outer surfaces of the side walls. Each block is made in two oppositely disposed sections 70 having their inner ends abutting each other in a vertical plane. The upper portion of the inner ends of the sections of each block are provided with oppositely disposed right angle grooves or channels 25 forming an inverted U-shaped channel extending the 75 length of the block, with said U-shaped channels of the series of blocks of each pier 17 forming a channel 26 that extends the length of the pier. The inner abutting ends of the 80 block sections are provided with oppositely disposed vertical channels 28 forming squared air ducts leading into the channel 26. The bottom sides of the block sections 85 are provided with oppositely disposed transverse channels 30 that form continuations of said vertical channels 28. The inner or upper walls 32 of the channels 30 are inclined 90 upwardly and inwardly. The block sections are provided with vertical longitudinal sides 34, and top sides or surfaces 36 that incline upwardly from the vertical sides 34 to the vertical walls of the longitudinally extending channel 26. The channel 26 of 100 each pier 17 is covered by cap blocks 38 of refractory material that rest on and are cemented to the top of the blocks 24 and are arranged end to end in staggered relation to the blocks 24. The under side of the cap blocks 105 38 are provided with a horizontal longitudinally extending central portion 40 of substantially the width of the channel 26, and with outer inclined portions 42 that fit the inclined top surfaces 36 of the block sections. 110

The under side of the caps are also provided with shallow transverse channels 44 which when the caps are in place lead from the horizontal channel 26, and are arranged in staggered relation to the vertical channels 28 in the abutting ends of the blocks. The top surfaces of the caps 38 are rounded transversely and the longitudinal sides of the caps are inclined upwardly and outwardly. The rear or bridge wall 8 of the fire-box is hollowed out to form an air chamber 46 which is connected at its lower end with a suitable source of air supply by a pipe 48. The air chamber 46 is in communication with the spaces between the intermediate partition 22 and the side walls 20 of each pier 17 through branch air passages 50.

The two outer piers 14 correspond to the portions of a pier 17 on opposite sides of a vertical plane extending through the center of the pier 17, each pier 14 having an outer side wall 20' corresponding to the wall 20 of the piers 17, an inner wall 22' corresponding to one half of an intermediate partition 22, a channel block 24' corresponding to a section of one of the blocks 24, a series of channeled caps 38' each corresponding to one half of one of the caps 38, and an air duct 50' in the bridge wall 8 leading from the air chamber 46 into the space between the outer wall 20' and inner wall 22' of each pier 14.

With this construction it will be apparent that upon air being admitted from the air chamber 46 to the spaces between the side walls and intermediate partitions of the piers 17 and between the walls 20' and 22' of the piers 14, the channel caps 38 and 38' will direct a portion of the air in thin films over the inclined top surfaces 36 of the blocks 24 and 24' and downwardly towards the troughs between the piers, and also that the air passages formed by the channels 30 in the under side of the block sections will direct thin films of air outwardly from the piers in a horizontal plane across the troughs. The air thus directed by the channel caps 38 and 38' over the inclined surfaces 36 of the blocks will serve to maintain these surfaces free from all deposits of cinders and other refuse and will keep the surfaces sufficiently cool to prevent them from wearing away or spalling. Also this air as it passes through the channels in the caps will maintain the caps below clinker forming temperature and as the upper longitudinal edges 52 of the caps overhang the ends of the channels 44 in the caps there will be no danger of clinkers or slag forming on these edges. As the longitudinal sides 34 of the blocks 24 and 24' project beyond the outer surfaces of the side walls of the piers there is no danger of the transverse channels 30 becoming clogged by clinkers forming over their outer ends. As the air passes over the outer edge of the inclined surfaces 36 of the blocks 24 and 24' the furnace draft will tend

to cause the air to pass upwardly toward the burning fuel and such tendency of this air to pass upwardly will be increased by the horizontal films of air passing through the horizontal channels 30 in the blocks, the horizontal films of air tending to break up the films of air passing over the inclined surfaces 36. Thus the films of air passing from the interior of the piers will be drawn up through the furnace by the furnace draft which will aid combustion and also tend to hold in suspension the heavier particles of fuel not completely burned that would ordinarily fall to the bottom of the furnace. These heavier particles will thus be more completely burned before finally settling in the troughs between the piers.

From the foregoing it will be apparent that all of the cinders and other refuse from the burning fuel will settle in the troughs and that it may be easily removed from the troughs through the openings 18 that are closed by the doors 19. The construction of the piers is such as to provide for the admission of air into the fire-box through the bottom thereof without danger of the air passages becoming blocked or clogged.

The four vertical walls of the fire-box of the illustrated construction is provided with three rows of blocks 54 having downwardly and inwardly inclined air ducts 56 in communication with the air chamber 46. These air ducts are arranged to direct films of air downwardly over the surface of the fire-wall and below the mass of burning fuel and inwardly toward the fuel. As the air thus passes below the mass of burning fuel the furnace draft draws the air inwardly and upwardly through the furnace to cooperate with the air rising from the piers 14 and 17 to aid combustion and to assist in holding the heavier particles of the burning fuel in suspension. It will be apparent that the downward admission of air from the front and side walls of the fire box of the furnace would tend to cause the heavier particles to take a long travel through the combustion chamber, and the more or less horizontally directed streams at the bottom of the combustion chamber would tend to prevent the heavier particles from being forced to the bottom. The construction and arrangement of the blocks 54 are described and claimed in my co-pending application filed of even date here-with.

While the features described above are well adapted for use in the type of furnace illustrated in the drawings, it is to be understood that, except as defined in the claims, certain features of the invention are not limited to use in a furnace embodying any or all of the other features as they may be used in other types of furnaces.

What I claim is:

1. A pulverized fuel furnace of the class

described having, in combination, a fire-box, means for introducing fuel into the upper portion of the fire box and piers at the bottom of the fire-box forming troughs between them and having provision for directing currents of air outwardly from the piers and downwardly toward the bottom of the troughs and for directing other currents of air horizontally across the troughs in a plane below the points of admission of the first mentioned currents of air.

2. A pulverized fuel furnace of the class described having, in combination, a fire-box, means for introducing fuel into the upper portion of the fire-box, piers extending longitudinally of the bottom of the fire-box, and spaced apart, and means for directing currents of air over and substantially parallel with portions of the top surfaces of the piers to cool and maintain these surface portions free of deposits of cinders and other refuse from the burning fuel.

3. A pulverized fuel furnace of the class described having, in combination, a fire-box, means for introducing fuel into the upper portion of the fire-box, piers forming troughs at the bottom of the fire-box, and means for directing currents of air over portions of the top surfaces of the piers and downwardly into the troughs.

4. A pulverized fuel furnace of the class described having, in combination, a fire-box, means for introducing fuel into the upper portion of the fire-box, and a pier at the bottom of the fire-box having a portion of its top surface inclined downwardly, an air passage extending longitudinally thereof, air ducts arranged to direct air from the air passage over said inclined surface, and air ducts in a side wall arranged to direct air in a substantially horizontal direction to mingle with the air directed over said inclined surface.

5. A pulverized fuel furnace of the class described having, in combination, a fire-box, means for introducing fuel into the upper portion of the fire-box, a pier at the bottom of the fire-box comprising outer side walls, an intermediate partition spaced from the side walls, and a cover for the top of the pier having air passages for conducting air into the furnace from the spaces between the side walls and said partition, said pier having provision for admitting air into said spaces.

6. A pulverized fuel furnace of the class described having a fire box, means for introducing fuel into the upper portion of the fire box, a pier at the bottom of the fire box comprising upright outer side walls spaced apart, a partition between the side walls and spaced therefrom, a member extending over the top of the side walls having top surface portions inclined downwardly and outwardly from the longitudinal central portion thereof, having

air passages extending upwardly through its central portion and in communication with the spaces between said intermediate partition and the side walls, and having a plurality of horizontal air passages below said inclined surface portions in communication with said spaces between said intermediate partition and the side walls for directing currents of air outwardly in a horizontal direction from opposite sides of the pier, a cap covering said central air passages in said member and having air passages in its under side for directing currents of air over said inclined surface portions, respectively, and means for supplying air to said spaces between said intermediate partitions and said side walls.

7. A pulverized fuel furnace having, in combination, a combustion chamber having an outlet in an upper part thereof, means for admitting and burning fuel, means for admitting air inwardly through the upright walls of the combustion chamber, and means for admitting air centrally of the lower portion of the combustion chamber in streams converging with the streams from the upright walls.

8. A pulverized fuel furnace having, in combination, a combustion chamber having an outlet in an upper part thereof, means for admitting and burning the fuel, and means for directing currents of air in opposite directions from a substantially central portion transversely over the floor or bottom of the combustion chamber.

9. A pulverized fuel furnace having, in combination, a combustion chamber having an outlet in an upper part thereof, means for admitting and burning the fuel, and means for admitting in the neighborhood of the bottom of the flame a downwardly inclined stream of air in a direction transversely of the flame stream.

10. A pulverized fuel furnace having, in combination, a combustion chamber having an outlet in an upper part thereof, means for admitting and burning the fuel, and means for admitting in the neighborhood of the bottom of the flame stream a plurality of downwardly inclined converging streams of air.

11. A pulverized fuel furnace having, in combination, a combustion chamber having an outlet in an upper part thereof, means for admitting the fuel at a point such that the fuel and flame stream in progress through the chamber rises toward the outlet, and means for directing a downwardly directed body of air between the fuel and flame stream and chamber structure at a point well above the bottom of the chamber, and for admitting a body of air beneath the flame in a direction generally transverse of the first body of air.

12. A pulverized fuel furnace having, in combination, a combustion chamber having an outlet in an upper part thereof, means for admitting the fuel in an upper part of the chamber in a downward direction so that the fuel and flame stream reverts on itself in a substantially U-form, and means for admitting a downwardly directed body of air between the descending portion of the fuel and flame stream and chamber wall, and between the ascending portion of the fuel and flame stream and the chamber wall, and means for admitting a body of air beneath the flame in a direction transverse that of the downwardly directed air.

13. In a furnace, a combustion chamber

having a substantially vertical wall and a draft outlet, means for introducing a stream of pulverized fuel mixed with air downwardly into the combustion chamber so that it 20 takes a return bent course to the draft outlet, means for introducing air to the combustion chamber between the fuel stream and wall provided with an air orifice approximately the width of the wall and with means for directing the air downwardly along said wall and means for introducing air into the bottom of the combustion chamber comprising an orifice substantially the width of said wall, formed to direct the incoming air in a 25 substantially horizontal thin stream.

GEORGE PERCY JACKSON.
